UNITED STATES PATENT OFFICE.

PAUL WERNER SEEWER, OF LONDON, ENGLAND, ASSIGNOR TO THE ENGLISH ELECTRIC COMPANY LIMITED, OF LONDON, ENGLAND, A BRITISH COMPANY.

HYDRAULIC IMPULSE TURBINE.

Application filed November 15, 1922. Serial No. 601,122.

To all whom it may concern:

Be it known that I, PAUL WERNER SEEWER, a citizen of the Swiss Confederation, residing at London, England, have invented certain new and useful Improvements in Hydraulic Impulse Turbines, of which the following is a specification.

This invention relates to hydraulic turbines of the free jet impulse type and deals particularly with the runners of such turbines, with the object of producing a turbine of relatively high specific speed and of relatively small size for a given output. In proceeding towards this end there is provided, in accordance with this invention, a form of runner adapted to work efficiently with a lower ratio between the mean diameter of the wheel and that of the jet than usual. For instance, this ratio may have

the value six.

A runner constructed in accordance with the invention departs from what is now recognized as standard practice both in regard to the form of the buckets and that of the body of the wheel and the relative disposition of these parts. The body of the wheel is formed so that in radial section it shows a central sharp edge from which the sides curve symmetrically radially inward and axially outward until they lie approximately parallel with the axis of the shaft. The curvature may be continued in the same sense past these points, in some cases. These curved sides form concave surfaces against which the radially inner parts of the buckets fit.

The buckets in the central part do not project radially outward beyond the edge of the body of the wheel. Accordingly, they do not present a central dividing edge or "splitter" to the jet. The place of this is taken by the edge of the wheel which divides the jet and deflects the two parts laterally to the buckets.

The buckets do not begin to extend radially outward beyond this central edge until points displaced laterally from this edge by distances equal to the radius of the jet have been passed. Beyond these points, outward extensions are formed of a size and shape sufficient to provide for the desired degree of completion of the transfer of energy to the wheel from those parts of the jet which are the last to enter the buckets. The side parts of the buckets have the general form

of the usual oval bowl with the edges directed so as to discharge the jet in directions relative to the moving bucket approximately opposite to the direction of motion of the bucket. The central parts of the buckets are formed as inclined surfaces extending from the bottom of the bowls to the adjacent parts of the body of the wheel so as to receive the water from this body and continue its lateral deflection.

The buckets are arranged close together circumferentially so that, for instance, the bottom of one bowl lies on or inside the plane of the outer edge of the next. The pitch of the buckets should not be greater than the largest diameter of the jet of water.

In the preceding description it has been assumed that the runner is symmetrical about a central plane. It is, however, to be understood that the invention is also applicable to the case where the runner is one-sided, that is where the construction of the runner corresponds to the part on one side of the central plane of a symmetrical runner. In such a case the general characteristics of the construction would be the same as in the symmetrical case, relative proportions being modified, where necessary, to allow for the changed conditions, notably that the whole of the jet is directed so as to strike the runner at one side of the plane of the edge instead of being divided by that edge.

Methods of construction suitable for the improved runner will now be described by way of example with reference to Figures 1 to 4 of the accompanying drawings. Figure 1 shows an end view and three buckets only of a runner wheel looking towards the sides of the buckets, certain interrupted lines being shown to indicate more clearly the shape of the buckets. The buckets are spaced as shown continuously around the wheel. Figure 2 shows a radial section through the body part of the wheel, for example on the line α of Figure 1, and a view of the pair of uppermost buckets in Figure 1 (one bucket being on each side of the central splitting edge of the body) looking in the direction of the arrow and assuming that all buckets hiding this view have been removed. Figure 3 is a perspective view of a complete runner of the kind shown in Figures 1 and 2. Figure 4 is a radial section and view similar to Figure 2 of a modified form of construction.

Referring to Figures 1, 2 and 3 where the same parts are indicated by the same numerals, the body 1 of the runner wheel is mounted upon the shaft 2 and the body 5 has a central sharp edge 3 from which the sides curve symmetrically radially inward and axially outward forming concave surfaces until at the edges 4 they have passed somewhat beyond parallelism with the axis 10 of the shaft. The buckets 5 which are first formed separately and preferably of the same material, such as bronze, as the body 1, are cast into these concave surfaces of the body 1 in such a manner that their inner 15 surfaces blend with the said concave surfaces of the body thus forming continuous smooth surfaces for the action of the water. The front edges of the buckets are shown by 10 and their rearmost contour lines by 20 6 and the corresponding inner lines by the interrupted lines 7. The lines 8 represent the radially outer contour lines of the buckets which blend together at the edge 3 of the body. Areas of junction between the 25 body material and the buckets are shown at 9 and the diameter and direction of the impinging jet of water are indicated by 11. The water flows out from the buckets at the edges 10 between limiting lines such as shown 30 at 12 and an idea of the space available for the outflowing water can be obtained from an examination of Figures 2 and 3. Supporting rings 13 for reinforcing the buckets are cast around the outer peripheries of the 35 latter and connected therewith as shown. These rings may be cast when the body and buckets are being cast together by leading the molten metal through suitable ducts into moulds formed in the sand in the required 40 positions.

The modifications in the form of construction shown in Figure 4 are introduced more particularly to allow the buckets to be so shaped that the outflowing water may leave 45 them without interruption in a direction which is more radial to the runner wheel than is possible in the construction shown in Figure 1. Similar parts in Figures 1 and 4 are indicated by the same numerals and in Figure 4 it will be observed that the supporting and reinforcing rings 13 are placed nearer to the center line of the body and that the shape of their edges adjacent to the buckets conforms to the contour line of the 50 edges of the buckets, and thus the outflow of the water, although it may take place in part near these rings, will not be interfered with by them.

From the drawings taken in conjunction 60 with the preceding description will be seen that certain dimensional relations previously referred to are obtained.

The radial outer edges 8 of the buckets do not extend radially outward beyond the 65 edge 3 of the body until they have extended

laterally from this edge to a distance equal to the radius of the full jet.

The pitch of the buckets, which is, as usual, measured on the circle 14 to which the centre line of the jet is a tangent, is 70 not greater than the diameter of the full jet.

The bottom of the bowl of any one bucket is seen to lie inside the plane of the outer edge 10 of the next bucket.

The deflection of the streams into which 75 the jet is broken is effected in the first place by the side of the body adjacent the edge 3, from which it passes on to parts of the buckets which may be regarded as vanes or 80 ribs projecting from the body, and which lead the water into the bowls of the buckets in which the main part of the tangential component of motion of the water relative to the runner is reversed.

From the preceding description it will 85 have been noted as a feature of the invention that the runner structure may be considered as divided by planes parallel with the plane of the central edge 3 into inner 90 and outer parts, the inner part being equal in width to the full width of the jet of water. This inner part being the region in which the water from the jet enters the runner, may be spoken of as the zone of 95 entry, and it comprises the radially outer 100 part of the body and the vanes or ribs projecting therefrom. The outer part, namely, the region outside the zone of entry, comprises the bowls which correspond approximately to the bowls of an ordinary runner. The improved runner may accordingly 105 be regarded as one in which the two halves of the ordinary buckets are separated and spaced apart by the zone of entry.

What I claim as my invention and desire 105 to secure by Letters Patent is:—

1. A runner for a free jet hydraulic impulse turbine comprising a body formed as a solid of revolution having an outer edge and a side curving radially inward and away from the plane of the said edge so as to show in radial section a concave face, buckets fitting on this face and extending laterally therefrom, the said buckets remaining within the radius of the said edge 110 for a distance equal to the width of the zone of entry of the water to the runner and extending outside that radius at parts where the water flows out from them.

2. A runner for a free jet hydraulic impulse turbine comprising a body formed as a solid of revolution having an outer edge and a side extending radially inward and away from the plane of said edge so as to deflect axially the jet of water which strikes the body, vanes projecting from the said side so as to continue the deflection of the water, bowls forming continuations of said vanes and receiving the water therefrom, said bowls having their lateral 120 125 130

edges, over which the outflow of the water takes place, extending radially outside of the outer edge of the said body.

3. A runner for a free jet hydraulic impulse turbine comprising a body and bowl shaped buckets mounted thereon, the pitch of the buckets being as a maximum equal to the diameter of the full jet of water, this pitch being measured on a circle about the 10 axis of the runner to which circle the centre line of the jet is a tangent.

4. A runner for a free jet hydraulic impulse turbine comprising a body showing in radial section a sharp outer edge and a 15 concave face extending inward from said edge at each side thereof, buckets fitting on these faces, the pitch of the buckets being as a maximum equal to the diameter of the

full jet of water, this pitch being measured on a circle about the axis of the runner to 20 which circle the centre line of the jet is a tangent.

5. A runner for a free jet hydraulic impulse turbine, comprising a body formed as a solid of revolution having an outer edge 25 and a side curving radially inward and away from the plane of the said edge, so as to show in radial section a concave face, buckets formed as oval bowls fitting on this face and extending laterally therefrom, the buckets being so located circumferentially that the bottom of the bowl of any one bucket lies within the mouth of the bowl of the next bucket.

In testimony whereof I affix my signature
PAUL WERNER SEEWER.
